(57) **CLAIM**

The design for a tire, as shown and described.

DESCRIPTION

FIG. 1 is a perspective view of a tire showing the new design.

FIG. 2 is a front view of a tire showing the new design.

FIG. 3 is a rear view of a tire showing the new design.

FIG. 4 is a top view of a tire showing the new design.

FIG. 5 is a bottom view of a tire showing the new design,

FIG. 6 is a first side (left) view of a tire showing the new design; and,

FIG. 7 is a second side (right) view of a tire showing the new design.

In the drawings, the broken lines depict environmental subject matter only and form no part of the claimed design. It is understood that the stippled shading represents grooves having the configuration and depth as shown at the top and bottom of FIGS. 2 through 5.
